CLAIM

We claim the ornamental design for a remote controller for LCD video projector, as shown and described.

DESCRIPTION

FIG. 1 is a top, rear and right side perspective view of a remote controller for a LCD video projector of the present invention;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.
